DESIGN FOR A LOCOMOTIVE

Charles J. Scudder, Scranton, Pa.

Application January 14, 1937, Serial No. 67,056

Term of patent 7 years

To all whom it may concern:

Be it known that I, Charles J. Scudder, a citizen of the United States, residing in the city of Scranton, county of Lackawanna, and State of Pennsylvania, have invented a new, original, and ornamental Design for a Locomotive, of which the following is a specification, reference being had to the accompanying drawing, forming a part thereof.

Fig. 1 is a side elevational view of a locomotive showing my new design, and

Fig. 2 is a front elevational view.

It is to be understood that the side of the locomotive opposite to the one illustrated in Fig. 1 is identical therewith and the rear end of the locomotive is conventional in design.

I claim:

The ornamental design for a locomotive, as shown and described.

CHARLES J. SCUDDER.
